US0D1078021S

(12) **United States Design Patent** (10) **Patent No.:** **US D1,078,021 S**
(45) **Date of Patent:** **** Jun. 3, 2025**

(54) **AIR CURTAIN DIFFUSER**

(71) Applicant: **FM PARTEC S.P.A.**, Correggio (IT)

(72) Inventor: **Gian Carlo Franchini**, Correggio (IT)

(73) Assignee: **FM PARTEC S.P.A.**, Correggio (IT)

(**) Term: **15 Years**

(21) Appl. No.: **29/949,887**

(22) Filed: **Jun. 28, 2024**

Related U.S. Application Data

(62) Division of application No. 35/514,348, filed on Nov. 26, 2021 (U.S. filing date under 35 U.S.C. 384), and having an international filing date of Nov. 26, 2021.

(57) **CLAIM**

The ornamental design for an air curtain diffuser, as shown and described.

DESCRIPTION

FIG. 1 is a front and side perspective view of an air curtain diffuser according to my new design;

FIG. 2 is a top plan view thereof;

FIG. 3 is a front elevation view thereof;

FIG. 4 is a rear elevation view thereof;

FIG. 5 is a bottom plan view thereof;

FIG. 6 is a right side elevation view thereof; and,

FIG. 7 is a left side elevation view thereof.

The broken line shown is for the purpose of illustrating portions of the air curtain diffuser that forms no part of the claimed design.

1 Claim, 7 Drawing Sheets
